PENDANT-TYPE DRAWER PULL

Lawrence McCain, Beverly Hills, and Raymond Tintary, Covina, Calif., assignors to Ajax Hardware Manufacturing Corp., City of Industry, Calif.

Filed Nov. 3, 1969, Ser. No. 19,915

Term of patent 14 years

Int. Cl. D8—03

U.S. Cl. D8—169

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 1 is a front elevational view of the design for pendant-type drawer pull;

FIG. 2 is a side elevational view thereof;

FIG. 3 is a rear elevational view thereof;

FIG. 4 is a bottom plan view thereof;

FIG. 5 is a top plan view of the pendant portion thereof with the retainer portion removed;

FIG. 6 is a vertical sectional view of the pendant portion thereof with the retainer portion removed taken on the broken line 6—6 of FIG. 1;

FIG. 7 is a front elevational view of the retainer portion thereof with the pendant portion removed;

FIG. 8 is a side elevational view of the retainer portion thereof with the pendant portion removed;

FIG. 9 is a rear elevational view of the retainer portion thereof with the pendant portion removed;

FIG. 10 is a top plan view of the retainer portion thereof with the pendant portion removed;

FIG. 11 is a bottom plan view of the retainer portion

thereof with the pendant portion removed; and

FIG. 12 is a side elevational view of the pendant-type drawer pull mounted on a drawer surface.

The broken lines are for illustrative purposes only.

We claim:

The ornamental design for a pendant-type drawer pull, as shown and described.
